WALTER E. NAYLOR, OF CHICAGO, ILLINOIS, ASSIGNOR TO THE BEARDSLEY & PIPER COMPANY, OF CHICAGO, ILLINOIS, A CORPORATION OF ILLINOIS

APPARATUS FOR CHARGING RETORTS

Application filed February 5, 1927. Serial No. 166,053.

The invention relates to apparatus for charging retorts.

The object of the invention is to provide apparatus for expeditiously charging retorts, such, for example, as are used in the production of zinc. This object is attained primarily by providing a rotary projector which is adapted to sling forcibly or throw the material through inlets of the retorts and is conveniently movable so that it may be successively brought into position to charge all of the retorts. Another object of the invention is to provide improved apparatus which is adapted to simplify and expedite the charging of retorts with material to be smelted.

Other objects of the invention and the various advantages and characteristics of the present construction will appear from a reading of the following detailed description.

The invention consists in the several novel features hereinafter set forth and more particularly defined by claims at the conclusion hereof.

In the drawings: Fig. 1 is a side elevation (parts being shown in section) of a machine embodying the invention. Figs. 2 and 3 are oppositely viewed end elevations of the machine. Fig. 4 is a longitudinal section illustrating the conveyor for feeding material from the reservoir to the elevator. Fig. 5 is a transverse section on line 5—5 of Fig. 4. Fig. 6 is an elevation of the side of the machine at which the projector is mounted. Fig. 7 is a longitudinal section through the projector. Fig. 8 is a section on line 8—8 of Fig. 7.

The invention is exemplified in apparatus for charging a zinc smelting furnace, the front wall x' of which is provided with a series of horizontal rows of inlets x^2 , through which the material is delivered into the smelting chambers of the furnace. The apparatus comprises mainly, a carriage A upon which the charging apparatus is mounted so it may be transported to receive a supply of material and deliver it to one or more furnaces to be charged; a reservoir or container B mounted on the

carriage and adapted to receive and hold sufficient material to charge a number of retorts; an endless conveyor C which forms the bottom of the reservoir and is adapted to feed the material from the reservoir in regulated quantity; an elevator D which receives the material from the conveyor C and elevates it; a vertically swinging arm or frame E; a belt conveyor F mounted on and to move with the arm E, which receives material from the elevator; a rotary projector G which is adapted to sling the material through the inlets x^2 into the retorts of the furnace; mechanism J for raising and lowering the projector into different positions to charge the inlets at different elevations; an electric motor H, mounted on the carriage, for driving a shaft h' ; reversible transmission gearing K driven by the motor H, for propelling the carriage; driving mechanism L for the elevator D; driving mechanism M for the conveyor C; a control lever N for the transmission gearing K and a control lever O for the driving mechanisms L and M.

In the use of the apparatus for charging smelting furnaces, the ore is first pulverized and mixed with coke and a sufficient percentage of soda for a flux, and this pulverized material is usually delivered or stored in an overhead bin from which it may be quickly discharged into the reservoir B on the carriage A. This reservoir has a sufficient capacity to charge a large number of retorts so as to minimize the trips necessary between the overhead storage bin and the furnace.

The carriage comprises a frame composed of longitudinal beams a' and end-beams a^2 , all of which are secured together to form a rigid supporting frame; axles a^3 mounted in bearings a^4 on said frame; and flanged wheels a^5 which are adapted to run on rails a^6 usually laid in and extending longitudinally of the floor of the furnace room.

The reservoir B consists of a hopper having downwardly convergent side walls b' and end walls b^2 . The hopper is supported by beams c' which are supported by the two central beams a' of the carriage frame.

The bottom of the reservoir B is formed by the endless feed conveyor C, and the latter is composed of a series of overlapping slats c^2 on sprocket chains c^3 which extend 5 respectively around a pair of drive sprockets c^4 on a cross-shaft c^5 and around idler sprockets c^6 . Said shafts are journalled in bearings c^7 (Fig. 5) which are fixed to the beams c' . Adjacent the discharge end of

10 the conveyor C, an adjustable gate b^4 is provided to form an opening of variable size, through which the material will be discharged from the reservoir so as to regulate the rate at which the material will be 15 fed from the reservoir and to the projector.

The elevator D for the material comprises a vertically extending casing d' at one end of the reservoir B and suitably secured to the carriage; an endless chain d^2 , carrying 20 the elevator buckets d^3 ; an overhead idler sprocket d^4 for the chain d^2 ; a drive sprocket d^5 at one side of and in the lower portion of the casing d' ; and an idler sprocket d^6 in the lower portion of the casing 25 and at the other side of said casing. Sprockets d^5 and d^6 are disposed to guide a horizontal reach of the elevator chain over the bottom of the casing d' , so that the buckets will be filled with material. The 30 reach between sprockets d^5 and d^4 is inclined so that a single upper sprocket will suffice to guide the elevator-chain. The material from the conveyor C is discharged through an opening in one side of the casing d' onto the bottom thereof. A deflector d^7 directs the discharged material into 35 said casing. Sprocket d^5 is fixed to a shaft d^8 which is journalled in bearings d^9 which are secured to the carriage frame. The 40 shaft for overhead sprocket d^4 is mounted in adjustable bearings d^{10} so that the elevator chain may be kept taut. The upper part of the casing d' is provided with a discharge spout d^{11} through which the material, elevated by the buckets d^3 will be discharged in a downwardly direction at one 45 side of the elevator casing d' .

The material projector G comprises a casing g' and a rotor g^2 provided with an 50 inclined plate g^3 which is adapted to pack the material under the influence of centrifugal force against the rim of the casing and to discharge it laterally from the casing through a spout g^4 projecting from one 55 side of the casing and at the correct angle to cause the material to be thrown through the usual inclined inlets x^2 of the furnace. The projector casing is fixed to the distal end of the arm E so that the projector may 60 be raised and lowered into position to discharge the material into inlets located at different elevations in the front wall of the furnace. The arm comprises a tubular member e' , to the outer end of which the 65 projector casing g' is fixed, and a gear

housing e^2 , to which the inner end of the member is attached. An electric motor e^3 has its casing secured to the gear casing e^2 to form a unitary part of the arm. The motor casing is bolted to a bracket e^4 which is fixed to a shaft e^5 which is journalled in bearings e^6 which are fixed to one end of the elevator casing d' . This exemplifies a projector which is pivotally supported so as to swing vertically to permit the material 70 to be discharged into inlets of retorts located at different elevations. The shaft e^5 of the electric motor e^3 extends through the gear-case e^2 and tubular member e' , and the hub of the rotor g^2 is fixedly secured 75 to the outer end of said shaft inside of the casing g' .

The conveyor F for delivering the material from the elevator into the projector casing comprises an endless belt f' , an idler pulley f^2 , journalled adjacent the inner side of the projector casing g' , and a driven pulley f^3 mounted adjacent the gear-casing e^2 . A hopper f^4 is supported by bars e^7 which are suitably supported from the member e' to direct the material from the discharge spout d^{11} of the elevator onto the conveyor-belt f' which delivers the material into an opening in the inner side of the projector casing g' where it will be caught by the rapidly rotating projector blade g^3 . The speed of the latter ranges around 1200 revolutions per minute, so that the pulverized material will be packed into wads by centrifugal force and forcibly projected 90 through spout g^4 into the rotor. Belt f' is constantly driven from the motor e^3 while the projector is in operation, by means of gearing comprising a bevelled gear f^5 fixed to the shaft e^6 , bevelled gear f^6 meshing with gear f^5 , a sprocket-wheel f^7 fixed to rotate with gear f^6 , a sprocket chain f^8 driven by sprocket f^7 and a sprocket wheel f^9 fixed to rotate the drive pulley f^3 for the belt f' . This exemplifies a pivotally movable supporting unit for the projector head which carries a conveyor and in which the several parts are enclosed, so that the pulverized material will not work into the driving mechanism. 100

The projector is raised and lowered by means of a cable e^{10} which passes around overhead sheaves e^{11} mounted on cross-head e^{12} fixed to the upper end of a standard e^{13} which is supported by the carriage, a drum e^{14} on which the cable is wound, so that the cable may be raised to lift the projector or paid out to lower it, and a crank e^{15} , by which the drum may be operated. A ratchet e^{16} is provided to prevent the cable 110 from unwinding. This exemplifies means for raising and lowering the supporting arm for the projector which is pivoted to swing vertically and for locking it in desired elevation. 120

The motor H is mounted at one end of the carriage-frame and is adapted to furnish the power to drive the transmission gearing for the carriage and the elevator and the feed conveyor C. The shaft h' of the motor H is provided with a pinion h². The transmission gearing K comprises a gear k' which meshes with the pinion h²; a shaft k², to which the gear k' is fixed, and which is rotatably mounted and longitudinally slidable in bearings k³ of the gear-case; two oppositely facing conoidal friction integrally formed with an extension of said case; two oppositely facing conoidal friction pulleys k⁷ and k⁸, which are fixed to the shaft k² and rotatable and longitudinally movable therewith; a large tapered friction pulley k⁹, with the opposite sides of which pulleys k⁸ and k⁷ are adapted to engage to 5 drive it in either direction; a cross-shaft k¹⁰, which is journalled in bearings k¹¹ which are fixed to the beams c'; a sprocket wheel k¹², fixed to shaft k¹⁰; a sprocket chain k¹³ driven by said sprocket-wheel and a 10 sprocket-wheel k¹⁴ which is keyed to rotate the axle a³ of one pair of the wheels a⁵ which serve as traction wheels. A collar n' is fixed to one end of the shaft k² and is adapted to be shifted longitudinally by the 15 controller lever N to shift the drive pulley k⁷ into engagement with the pulley k⁸ and in reverse direction to bring the drive-pulley k⁸ into engagement with the pulley k⁹, as well as into a neutral position, in which both 20 of the pulleys k⁷ and k⁸ will be disengaged from the pulley k⁹. Lever N is fixed to a cross-shaft n² which is pivoted in bearings n³ which are fixed to one of the end beams a². The operating connection for lever N 25 comprises an arm n⁴ fixed to the cross shaft; a link n⁵ pivoted to the free end of arm n⁴; and a lever n⁶ which is pivoted to the link, fulcrumed on the carriage frame at n⁷ and pivoted at n⁸ to a ring n⁹ which is confined 30 in an annular groove in the collar n'. This exemplifies reversible transmission gearing for driving the truck in opposite directions and for controlling the gearing by means of a lever. An operator's platform n¹⁰ is suitably supported from the carriage frame at one end thereof, so that the operator may ride on the carriage and conveniently control its movements. 35

The mechanism L for driving the elevator 40 comprises a pinion l' fixed to rotate with the shaft k²; a gear l², meshing with pinion l' and enclosed in the gear-case k⁴; a shaft l³, journalled in the gear-case k⁴ and in a bearing bracket l⁴ fixed to the carriage frame, 45 and on which gear-wheel l² is loosely mounted so it may rotate independently of the shaft; a sprocket wheel l⁵ fixed to the shaft l³; a sprocket chain l⁶; and a sprocket wheel l⁷ fixed to the shaft d⁹ to which the elevator drive-sprocket d⁵ is secured. 50

The mechanism M for driving the conveyor C comprises an eccentric m' fixed to rotate with the shaft l³; a collar m³ held in a groove in the eccentric m'; links m⁴ pivoted at m⁵ to collar m³; a lever m⁶, to one end of which the links m⁴ are pivoted, a pawl m⁷ operated by the lever m⁶; and a ratchet wheel m⁸ which is fixed to the shaft c⁵ which carries the drive sprocket c⁴ for the chains c³ of the feed conveyor C. This mechanism serves to intermittently operate the conveyor which forms the bottom of the reservoir to discharge a regulated quantity of the material from the reservoir into the elevator casing d'. 55

Lever O for controlling the elevator and the feed conveyor has its upper end secured to a rock-shaft o' which is pivoted in lugs o² secured to one end of the reservoir B. The operating connections for the lever 60 comprise a depending arm o³ fixed to shaft o', a link o⁴, pivoted to the free end of arm o³, an arm o⁵ pivotally connected to link o⁴ and fixed to a shaft o⁶ which is journalled in the gear-case k⁴, an arm o⁷, fixed to the shaft o⁶ inside of the crank case and forked to shift a movable clutch member o⁸ which is splined to the shaft l³ and adapted to interlock with complementary clutch teeth on the gear l², so that when said clutch-members interengage, the gear wheel l² will drive the shaft l³, through the clutch, and when the clutch members are disengaged, the shaft l³, the elevator and the feed conveyor 65 will be idle. 70

The operation will be as follows: Assuming the machine to be in position to receive a load of pulverized material with which the retorts are to be charged, the reservoir B will be filled with such material. The operator, by means of lever N will control the reversible transmission gearing to propel the carriage from the loading place across the front of the furnaces or retorts until it is positioned adjacent the retorts to 75 be charged. The projector head G may then be raised or lowered, if necessary, to bring the discharge spout g⁴ of the projector into substantial registry with one of the inlets to a retort. The operator will then 80 shift the lever O to couple the gear l² and the clutch member o⁸, so that shaft l³ will be continuously driven. The mechanism M will slowly operate the feed conveyor C to 85 deliver pulverized material from the reservoir to the elevator D. The latter will deliver the material as received from the feed-conveyor and discharge it through the spout d¹¹ into hopper f⁴ on the projector arm E and onto the endless feed belt f' which will 90 feed the material into the casing g'. The propeller blade g³ on the rotor of the projector will compact the material into wads, and under the action of centrifugal force, the wads will be formed adjacent the periph- 95 100

ery of the casing g' and then forcibly discharged laterally through the spout g^4 and the inlet x^2 into the retort. The retort will then be closed as well understood in the art 5 until the material has been properly smelted. The machine may, through the reversible transmission gearing K, be propelled into position adjacent different vertical rows of inlets x^2 , and by raising and 10 lowering the projector head, it may be positioned to project the material through the inlets at different elevations. Thus, the machine is adapted to fill any of the usual vertical or horizontal series of retorts with 15 material from the reservoir B, until the load of material has been used. The operator will then operate the control lever O to stop the feed conveyor C and elevator H, and then manipulate the lever N to control the 20 reversible transmission gearing K to propel the machine into position to receive another load of material from the overhead bin or other suitable source of supply.

The invention exemplifies a machine for 25 charging zinc smelting furnaces and the like, in which the charges are expeditiously thrown into the retorts by means of a high speed projector; in which the projector is mounted on a movable carriage which may 30 be readily propelled between different furnaces and to and from the source of supply of pulverized material; which is adapted to transport a large quantity of the material so that a large number of retorts may be 35 charged from a single load to minimize the trips necessary in loading the reservoir; in which the projector is vertically adjustable to charge retorts located at different heights from the floor, and which is well adapted 40 for use in charging zinc smelting furnaces to expedite the charging and prevent losses which result from delay in charging.

The invention is not to be understood as restricted to the details set forth, since these 45 may be modified within the scope of the appended claims, without departing from the spirit and scope of the invention.

Having thus described the invention, what I claim as new and desire to secure by Letters Patent, is:

1. In apparatus for charging furnaces, the combination of a movable carriage, a reservoir for the material mounted on the carriage, an endless conveyor for feeding material from the reservoir, a rotary projector for throwing material, provided with means to discharge laterally, into the furnace, and means for delivering material from the conveyor to the projector comprising an 55 elevator.

2. In apparatus for charging furnaces, the combination of a movable carriage, a reservoir mounted on the carriage, an endless conveyor forming the bottom of the 60 reservoir, a vertically movable rotary projector

for throwing material, and provided with means to discharge the material laterally, into the furnace, an elevator for receiving the material from the conveyor, and a conveyor movable with the projector and for delivering the material from the elevator to the projector.

3. In apparatus for charging furnaces, the combination of a movable carriage, a reservoir for the material on the carriage, an arm pivotally supported on the carriage to swing vertically, a rotary projector on and movable with the arm, an elevator at one end of the reservoir for receiving material therefrom, a conveyor mounted on and movable with the arm for delivering the material from the elevator to the projector, and a motor movable with the arm for driving the projector.

4. In apparatus for charging furnaces having side inlets at different elevations, the combination of a movable carriage, a reservoir for the material mounted fixedly on the carriage, a projector for the material, comprising a rotor and a casing for the rotor having a single discharge nozzle arranged to project the material laterally, means mounted on the carriage for supporting the projector so that it may be moved vertically into position to project the material through said inlets, and means for delivering the material from the reservoir to the projector, comprising a conveyor movable with said projector.

5. In apparatus for charging furnaces, the combination of a movable carriage, an arm pivotally connected to the carriage so as to swing vertically alongside of one side thereof, a rotary projector for throwing material, mounted on the distal end of said arm, and means for feeding material to the projector.

6. In apparatus for charging furnaces, the combination of a movable carriage, an arm pivotally connected to the carriage so as to swing vertically alongside of one side thereof, a rotary projector for throwing material, mounted on the distal end of said arm and provided with a discharge nozzle arranged to project the material laterally with respect to said carriage, and means for feeding material to the projector.

7. In charging apparatus, the combination of a movable carriage having laterally extending shaft at one side thereof, an arm pivoted to said shaft and adapted to swing vertically alongside of said side of the carriage, a rotary projector for throwing material mounted on the distal end of said arm, and means for feeding material to the projector.

8. In charging apparatus, the combination of a movable carriage having a laterally extending shaft at one side thereof, an arm pivoted to said shaft and adapted to

swing vertically alongside of said side of the carriage, a rotary projector for throwing material mounted on the distal end of said arm, and means for feeding material to the projector mounted on and movable with the arm.

9. In charging apparatus, the combination of a movable carriage, an arm arranged alongside of and substantially coextensive with one side of the carriage, one end of the arm being pivoted to swing vertically, a rotary projector for throwing material mounted on the other end of the arm, means for feeding material to the projector, and means for raising and lowering the arm to shift the points of delivery of the projector.

10. In charging apparatus, the combination of a movable carriage, an arm arranged alongside of and substantially coextensive with one side of the carriage, one end of the arm being pivoted at one end of the carriage so that it may be swung vertically adjacent said side, a rotary projector for throwing material mounted on the other end of the arm, means for feeding material to the projector, and means at the other end of the carriage for raising and lowering the arm to shift the points of delivery of the projector.

11. In charging apparatus of the character described, the combination of a wheeled carriage, a reservoir for the material mounted on the carriage, an arm pivotally supported at one end of said carriage to swing vertically adjacent one side of the reservoir, a rotary projector for throwing the material mounted on the distal end of the arm, an elevator for the material at said one end of the carriage, a conveyor mounted on and movable with the arm for delivering the material from the elevator to the projector, and means at the other end of the carriage for raising and lowering the arm to shift the points of delivery of the projector.

12. A machine for charging retorts comprising a frame, a pivot on which said frame is supported for vertical swinging movements, a projector at one end of said frame, a motor at the opposite end of said frame, a conveyor supported by said frame for conveying materials to said projector, a receptacle extending below the plane of said conveyor, elevator mechanism for delivering materials from said receptacle to said conveyor, and mechanism for operating said elevator mechanism.

13. A machine for charging retorts comprising a pivotally supported projector, means for supporting said projector at different heights, a motor for operating said projector, a conveyor for conveying materials to said projector, elevator mechanism for delivering materials to said conveyor, a container for the materials to be projected

by said projector, and a conveyor for conveying said materials from said container to said elevator mechanism.

14. A machine for charging retorts comprising a pivotally supported projector, means for supporting said projector at different heights, a motor for operating said projector, a conveyor for conveying materials to said projector, elevator mechanism for delivering materials to said conveyor, a container for the materials to be projected by said projector, a conveyor for conveying said materials from said container to said elevator mechanism, a motor, and mechanism operated by said motor for operating said elevator mechanism and said last named conveyor.

15. A machine for charging retorts arranged in tiers comprising a conveyor operating transversely of the planes of the axes of the retorts to be charged, a discharge nozzle extending approximately parallel with the plane of the axes of the retorts, a projector for throwing through said discharge nozzle the material dumped from said conveyor, and means for supporting said projector and said nozzle at different heights in each of which said nozzle extends in a direction approximately parallel with its direction of extension at any other height.

16. A machine for charging retorts arranged in tiers comprising a conveyor operating transversely of the planes of the axes of the retorts to be charged, a projector, an approximately horizontal nozzle for said projector extending approximately parallel with the plane of the axes of the retorts, a horizontal pivot supporting and permitting the projector to be moved vertically while the nozzle remains approximately horizontal, a device for moving the projector vertically, and mechanism for conveying material to and operating the projector in any of the positions thereof.

17. A machine for charging retorts arranged in tiers comprising a conveyor operative transversely of the planes of the axes of the retorts to be charged, a rotary projector for discharging material delivered thereto from said conveyor, an approximately horizontal nozzle for said projector, means for supporting the projector and the nozzle and permitting movements thereof to different vertical positions in each of which positions said nozzle extends in a direction approximately parallel with the direction of extension in any other position, means for moving the projector and the nozzle in different vertical positions, and mechanism for operating the projector in any of said positions.

18. A machine for charging retorts arranged in tiers comprising a conveyor operating transversely of the planes of the axes of the retorts to be charged, a projector for

- discharging materials delivered thereto from said conveyor, means for supporting the projector in different vertical positions, a discharge nozzle extending toward said 5 retorts for charging the retorts with materials thrown by said projector, mechanism for operating said conveyor and said projector, a container for the materials to be conveyed to the projector, mechanism for 10 conveying the materials from said container to said conveyor, and a device for regulating the amount of materials conveyed by said last-named mechanism from said container during a given period of operation.
- 15 19. A machine for charging retorts arranged in tiers comprising a stationary support, a frame pivoted on said support for vertical swinging movements transversely of the planes of the axes of the retorts to be 20 charged, means for supporting said frame in the different positions to which it is moved, a nozzle extending laterally from one end of said frame toward the retorts, a projector in said frame adjacent to said nozzle, a 25 motor at the opposite end of said frame, a conveyor supported by said frame for conveying materials to said projector, and mechanism for operating said projector and said conveyor by said motor.
- 30 Signed at Chicago, Illinois, this 21st day of January, 1927.

WALTER E. NAYLOR.
